UNITED STATES PATENT OFFICE.

REUBEN B. BENJAMIN, OF CHICAGO, AND CHESTER E. WARNER, OF BERWYN, ILLINOIS,
ASSIGNORS TO BENJAMIN ELECTRIC MANUFACTURING COMPANY, OF CHICAGO,
ILLINOIS, A CORPORATION OF ILLINOIS.

ATTACHMENT PLUG.

Application filed May 10, 1920. Serial No. 380,108.

To all whom it may concern:

Be it known that we, REUBEN B. BENJAMIN, a citizen of the United States, residing at Chicago, in the county of Cook and State of Illinois, and CHESTER E. WARNER, a citizen of the United States, residing at Berwyn, in the county of Cook and State of Illinois, have invented certain new and useful Improvements in Attachment Plugs, of which the following is a full, clear, concise, and exact description, reference being had to the accompanying drawings, forming a part of this specification.

Our invention relates to attachment plugs, and more specifically to attachment plugs for heavy duty, in which provision has to be made to prevent injury to the contacts due to the heavy current.

One of the objects of our invention is to provide an improved plug for heavy duty in which provision is made for preventing injury to the contacts in making the connection. We accomplish this by providing a switch mechanism carried by the plug, which switch mechanism is automatically moved to "on" position when the plug is inserted in the receptacle.

Further objects of our invention will appear from the description to follow and from the claims.

In the drawings, in which an embodiment of our invention is shown:

Fig. 1 is a side elevation of an attachment plug;

Fig. 2 is a top plan view of the plug shown in Fig. 1;

Fig. 3 is an axial section of the plug shown in Fig. 1;

Fig. 4 is an axial section of the plug on the line 4—4 of Fig. 3;

Fig. 5 is a transverse sectional view on the line 5—5 of Fig. 3;

Fig. 6 is a transverse sectional view on the line 6—6 of Fig. 3;

Fig. 7 is a section through the switch mechanism on the line 7—7 of Fig. 5.

Fig. 8 is a bottom view of the insulating plug base;

Fig. 9 is a top view of an insulating lower base;

Fig. 10 is a bottom view of the lower base;

Fig. 11 is a perspective view of the switch lever; and

Fig. 12 is a detail view of the switch arm. 55
In order to give a general idea of the construction shown, it is here stated, that it comprises a swivel plug for screwing into an Edison socket, the swivel shell contact of the plug being provided with a flexible 60 extension handle, the plug itself containing a snap switch mechanism actuated by the center contact of the plug, and being provided with binding terminals for conductors leading from the plug, and with cord-grip 65 means for relieving these binding terminals from strain due to a pull on the conductors.

Referring now to the construction in detail, the plug shown comprises an insulating base 15, a center contact 16 supported 70 thereby, a swivel shell contact 17 rotatably mounted with respect thereto, a flexible extension handle 18 connected with the swivel shell contact 17, a switch mechanism 19 mounted in the insulating base 15, binding terminals 20 and 21 for the conductors leading from the plug respectively, and an insulating screw cord-grip member 22 for gripping the conductors to relieve the binding terminals 20 and 21 from strain. 75
80

Referring particularly now to the construction of the switch mechanism 19, this is of the snap switch type, sometimes referred to as a "toggle" switch, and comprises an oscillatable switch lever 23, an oscillatable 85 switch arm 24, a link 25 extending between the switch lever 23 and the switch arm 24, a coil-compression spring 26 surrounding the link 25, and exerting a pressure tending to force the switch arm 24 away from the switch lever 23 and a coil-torsion-spring 27, tending to move the switch lever into a position corresponding to the "off" position of the switch. The switch lever 23 is engaged by and moved by an insulating button 28, which in turn is connected to move with the center contact 16 of the plug so that when the plug is screwed into the socket, the insulating button 28 will bear on the switch lever 23 to move the switch lever 23 to a position 90
95
100

which will cause the switch to snap to the "on" position. It will thus be seen that the member 23 is in effect a bell-crank member acting between the plunger 28 and the link 25.

The switch mechanism controls the electrical connection between the center contact 16 and the binding terminal 21, the other binding terminal 20 being always electrically connected with the threaded shell contact 17. The control of the circuit from the center contact 16 to the wiring terminal 21 is effected by the cooperation of the switch arm 24 with two spring contact members 29 and 30 respectively, the spring contact 29 being always electrically connected with the center contact 16, and the spring contact 30 being always electrically connected with the wiring terminal 21, and the switch arm 24 which is of conducting material serving to make or break the connection between the contacts 29 and 30. The spring contact 29 is formed as a part of an integral sheet metal stamping, this stamping comprising in addition to the U-shaped contact portion 29 a conducting strip portion 31 lying against the side of the recess in which the switch mechanism is located, and a contact portion 32, which has a sliding contact with a contact portion 33, which contact portion 33 is in electrical connection with the center contact 16. To assist in holding the contact 29 in place, the stamping is provided with an L-shaped extension 34 at its lower end, which fits into a correspondingly shaped recess in the insulating base 15, to hold the lower end of the stamping against movement. The center contact 16 is formed as a part of the integral sheet metal stamping, comprising a cylindrical portion 35 surrounding the insulating button 28, in addition to the sliding contact portion 33.

The contact portion 30 is formed as a part of an integral sheet metal stamping, which stamping comprises in addition to the U-shaped contact portion 30, a bent conducting strip portion 36 extending across the recess in which the switch mechanism is located, and extending downwardly to the binding screw 37 of the wiring terminal 21. This binding screw 37 extends through an opening in the conducting strip 36 and is threaded into a nut 38, which is seated in a recess in the insulating base 39, which supports the binding terminals 20 and 21.

The switch arm 24 comprises a U-shaped sheet metal stamping, which is pivotally mounted in a switch frame 40, by means of a pivot pin 41, which pivot pin also pivotally supports the switch lever 23.

The switch frame 40 may have a lug 42 struck up therefrom, for engagement with the link 25, to give a positive kick-off to the switch arm in case the yielding pressure of the compression spring 26 is insufficient to

start the switch arm in motion to the "on" position. The switch lever 23 may be a U-shaped sheet metal stamping, having a bearing portion 43 for engagement with the forked end of the link 25, and having positioning lugs 44 for holding the link 25 against lateral movement. This stamping is also provided with an opening 45 to receive the end 46 of the coil-torsion spring 27, the other end of which spring may bear against the web portion of the channel-shaped switch frame 40.

The wiring terminal 20 is electrically connected with the shell contact 17 by means of the sliding contact sleeve or cap 47, and a 80 conducting strip 48, leading from the sliding contact 47 to the binding screw 49 of the binding terminal 20. This sliding contact member 47 may be a sheet metal stamping, and may, in addition to serving as a contact, 85 act also to hold the insulating base 39 in place with respect to the insulating base 15. It is provided with an inwardly-extending flange portion 50 which extends underneath the flange portion 51 of the insulating base 90 39, and it has portions in its upper edge depressed inwardly as indicated at 52 into depressions or grooves 53 in the sides of the insulating base 15 to secure the conducting member 47 to the insulating base 15, to hold 95 the two insulating bases together.

The conducting member 49 has a portion clamped between the flange portion 50 of the contact 47 and the flange portion 51 of the insulating base 39. The binding screw 49 100 extends through an opening in the member 48 and is threaded into a nut 54 located in a recess in the insulating base 39.

For gripping the conductors which are connected with the binding terminals 20 and 21, the cord-grip member 22 is internally threaded, and is screwed onto the externally threaded portion 55 of the insulating base 39.

When the cord-grip member 22 is screwed up, it pinches the cord between the annular shoulder portion 56 of the cord-grip member and the tapered abutment 57 of the insulating base 39. The binding terminals 20 and 21 are located in recesses or pockets 58 and 59 in opposite sides of the insulating base 39, the threads of the insulating base being interrupted at these recesses.

For positioning the insulating base 39 with respect to the insulating base 15, the base 15 is provided with a downwardly extending lug or boss 60 which engages in a recess 61 in the flange portion of the insulating base 39.

The flexible handle 18 is connected to the threaded shell contact 17 by means of a sheet metal cup-shaped stamping 62, the lower portion of which is secured at 63 in any suitable manner, to the flexible handle 18, and the upper edge of which is flanged over an

insulating disc 64, which disc 64 is in turn secured to the threaded shell contact 17. The threaded shell contact is beaded over this insulating disc 64 as indicated at 65, 5 the upper portion of this bead serving as a contact portion for engagement with the sliding contact 47. The usual insulating sleeve or collar 66 is provided for insulating the lower portion of the threaded shell contact 17 when the latter is in engagement with the receptacle contact. The cup-shaped stamping 62 is provided with a pair of openings 67 on opposite sides to afford access to the cord-grip member 22 to enable the 10 cord to be gripped after the plug is wired and assembled.

The circuit through the plug has been outlined in connection with the description of the switch mechanism. Assuming that the 20 plug is screwed into the socket (and hence that the switch is in "on" position) the circuit will be from the center contact 16 through the sleeve portion 35, sliding contact 33, switch contact portion 32, conducting portion 31, contact 29, switch arm 24, contact 30, conductor 36, to the binding terminal 21, thence through whatever translating device is connected with the plug to the wiring terminal 20, to the contact member 45 30 47 to the threaded shell contact 17.

In wiring the plug, the inner construction including the two insulating bases 15 and 39 and the parts carried thereby are removed from the threaded shell contact 17, the plug member 22 being screwed off from the insulating base 39, to permit this removal, the conductors are led up through the flexible handle 18, and through the cord-grip member 22 and the threaded shell contact 17 and are secured to the wiring terminals 20 and 21, and the interior construction is then slipped back into the shell and the cord-grip member 22 screwed onto the threaded portion of the insulating base 39, to hold the parts together and to grip the cord.

When the plug is to be inserted into the socket, the threaded shell contact 17 is positioned properly with respect to threaded shell of the socket and is screwed into the socket, the flexible handle 18 being used if the socket is otherwise difficult of access. As the threaded shell contact is screwed into the socket, the center contact 16 will come into engagement with the center contact of the socket, and will be moved relatively to the rest of the plug, to cause the push button member 28 to actuate the switch lever 23, to cause the switch to snap from "off" to "on" position to quickly complete the circuit. This quick completion of the circuit prevents burning of the contacts and other undesirable effects which result when the circuit is completed slowly and uncertainly as is apt to be the case with the ordinary screw shell plug.

Similarly, when the plug is screwed out of the socket, the spring 27 will force the insulating button 28, which carries the center contact, outwardly with respect to the rest of the plug, and will keep the center 70 contact 16 in engagement with the center contact of the socket for a time, until the spring 27 has moved the switch lever 23 to a position which will cause the switch blade 24 to be moved to "off" position, thus 75 quickly breaking the circuit at two points and preventing arcing and burning of the contacts.

This breaking of the circuit at a point other than between the center contacts of the 80 plug-in socket also prevents the danger of arcing from the center contact of the socket to the center contact of plug and thence to the shell contact of the receptacle, which is apt to take place in heavy duty plugs, 85 which have no provision to prevent this arcing.

Having thus described our invention, what we claim as new and desire to secure 90 by Letters Patent is:

1. An attachment plug comprising a body-portion, a center contact mounted thereon, a shell contact swiveled thereon, said body-portion being insertable in said shell contact at the entering end thereof, 95 said body-portion having an extension projecting outwardly from said threaded shell contact, and two wiring terminals mounted on said extension, one of said terminals being electrically connected with the center contact, and the other terminal being electrically connected with the threaded shell contact, said extension and wiring terminal being withdrawable with said body portion 100 from the entering end of said shell contact. 105

2. An attachment plug comprising a two-part insulating base comprising an inner and outer part, a threaded shell contact swiveled about said insulating base, said inner base part being recessed and open at 110 its outer end, a switch mechanism located in said recess and insertable and removable through said open outer end, wiring terminals mounted on the outer part of said insulating base, a contact mounted on said outer base part, and extending into said recess for engagement with said switch mechanism, and another contact mounted on said outer base part extending up and slidably engaging said swivel shell contact. 115

3. An attachment plug comprising a two-part insulating base comprising an inner and outer part, a threaded shell contact swiveled about said insulating base, said inner base part being recessed and open at 120 its outer end, a switch mechanism located in said recess and insertable and removable through said open outer end, wiring terminals mounted on the outer part of said insulating base, a contact mounted on said 125 outer base part, and extending into said recess for engagement with said switch mechanism. 130

outer base part and extending into said recess for engagement with said switch mechanism, and means engaging said outer base part for holding said swivel shell in position.

4. An attachment plug comprising a two-part insulating base comprising inner and outer parts, a threaded shell contact swiveled on said insulating base, a recess in 10 said insulating base exposed on separating the parts of the base, switch mechanism in said recess, and means for holding the two parts of the base together comprising a sliding contact member engaging said 15 threaded shell contact.

5. A switch plug comprising an insulating base, a shell contact mounted thereon, a center contact member mounted thereon to slide longitudinally thereof, and a switch 20 mechanism for controlling the plug circuit comprising a switch blade located substantially within said shell contact and oscillat-

able back and forth, a spring shiftable back and forth past a dead center to cause quick action of the switch blade, and a 25 spring shifting member operated by said sliding contact member.

6. A switch plug comprising an insulating base, a shell contact mounted thereon, a center contact member mounted thereon to slide longitudinally thereof, and a switch mechanism for controlling the plug circuit comprising a switch blade located substantially within said shell contact and oscillatable back and forth, a spring shiftable 30 back and forth past a dead center to cause quick action of the switch blade, and a 35 pivoted spring shifting member operated by said sliding contact member.

In witness whereof, we have hereunto 40 subscribed our names.

REUBEN B. BENJAMIN.
CHESTER E. WARNER.
